2 SHEETS—SHEET 2.

UNITED STATES PATENT OFFICE.

HERBERT S. HUMPHREY, OF KALAMAZOO, MICHIGAN.

WATER-HEATER.

1,033,103.

Specification of Letters Patent. Patented July 23, 1912.

Application filed February 8, 1912. Serial No. 678,239.

To all whom it may concern:

Be it known that I, HERBERT S. HUMPHREY, a citizen of the United States, residing at the city of Kalamazoo, county of 5 Kalamazoo, and State of Michigan, have invented certain new and useful Improvements in Water-Heaters, of which the following is a specification.

This invention relates to improvements 10 in water heaters.

The main objects of this invention are, first, to provide an improved valve whereby the fuel supply to the heater is completely cut off or turned on when the temperature 15 rises above or falls below a predetermined point; second, to provide an improved thermostat actuated valve embodying these advantages which is very compact in structure and not likely to get out of repair.

20 Further objects, and objects relating to structural details, will definitely appear from the detailed description to follow.

I accomplish the objects of my invention by the devices and means described in the 25 following specification.

The invention is clearly defined and pointed out in the claims.

A structure which is a preferred embodiment of my invention is clearly illustrated 30 in the accompanying drawing, forming a part of this specification, in which:

Figure I is a detail side elevation of a structure embodying the features of my invention, the heater being shown in conventional form, a portion of the tank being 35 broken away to show the arrangement of the thermostat therein. Fig. II is an enlarged detail longitudinal section through the valve casing taken on a line corresponding to line 2—2 of Fig. III. Fig. III is an enlarged detail partially in section on a line corresponding to line 3—3 of Fig. II. Fig. IV is an enlarged detail section corresponding to Fig. II, showing the form and 45 arrangement of the parts. Fig. V is a transverse section taken on a line corresponding to line 5—5 of Figs. II and III.

In the drawing, similar reference characters refer to similar parts throughout the 50 several views, and the sectional views are taken looking in the direction of the little arrows at the ends of the section lines.

55 Referring to the drawing, the heater 1 is shown in conventional form as a coil heater and is provided with burners 2. The heater casing 3 is indicated by dotted lines.

The heater coils are connected by the pipes 4 and 5 to the tank 6. The water is delivered to the tank through the pipe 7. A draw-off faucet 14 is provided for the tank. 60

The gas is delivered to the burners through the supply pipe 8. The delivery of the gas is controlled by my improved valve which is automatically operated by the thermostat disposed within the tank 6 as illustrated. The thermostat illustrated consists of an outer tubular member 9 and an inner member 10. The valve casing 11 is provided with a seat 12 for the valve 13 and with a cylinder 14 alined with the seat. 70 The valve stem 15 is guided by the guide 16 provided therefor in the head 17 of the cylinder 14 and by a suitable gland 18 through which the stem projects to be engaged by the thermostat lever 19. This lever is pivoted at 75 20 and is acted upon by the lever 21 which is pivoted at 22 and is in turn actuated by the thermostat rod 10. The valve 13 is slidably mounted upon the valve stem, that is the valve stem and the valve are movably associated. The independent movement of the stem and valve is limited by the shoulder-like stop 23 and the stop pin 24. When the valve is closed or seated, it is out of engagement with both stops so that a limited movement of the stem is permitted without unseating the valve. 80

Arranged within the cylinder 14 above the valve, is a plunger or reciprocating member 25. This member is preferably 90 ring-like or annular, as illustrated. The valve stem is arranged to actuate this reciprocating or plunger member, the connection consisting of a pair of levers 26 which are pivoted on the ears 27 projecting inwardly 95 from the head or cap 17, the inner ends of the levers being arranged in the transverse slot 28 in the stem so that the levers are rocked on their pivots 29 when the stem is reciprocated. The outer ends of the levers 100 are connected to the reciprocating member 25 by means of the links 30. Return springs 31 are provided for the reciprocating member, the springs being secured to the cap or head 17 and to the member, and this through the connection described for the stem, returns the stem when the thermostat lever 19 is retracted. 105

The valve is actuated through the springs 32. These springs are mounted upon supports which in the structure illustrated are formed of telescoping sections 33 and 34, the 110

section 33 being pivoted to the ears 35 on the reciprocating member while the sections 34 are pivoted to the ears 36 on the valve. The springs are arranged on the support to bear 5 against the rests 37. When the valve stem is actuated by the thermostat, the reciprocating member through the connections to the valve stem, is moved toward the valve against the tension of the return springs 31 10 and collapses the springs 32 until the plane of the pivots 38 connecting the spring supports to the reciprocating member passes the plane of the pivots 39 connecting the spring supports to the valve. The springs 32 then 15 act upon the valve to open it with a snap action. When the valve stem is released, the return springs 31 return the reciprocating or plunger member and when the plane of the pivots 38 again passes the plane of the 20 pivots 39, on this return movement the springs 32 act to close the valve with the so-called snap action. With the parts thus arranged, the valve is fully opened or 25 closed. The quick or instantaneous opening and closing of the valve results in a decided saving of fuel and insures the prompt lighting of the gas from the pilot indicated at 40, Fig. I, as when the gas valve is 30 opened gradually, there is a possibility of the escape of considerable gas and forming of an explosive mixture before the gas is ignited from the pipe.

My improved valve is very simple and compact in structure and is not likely to get 35 out of repair. Further, the parts are all inclosed so that they cannot be accidentally displaced or disturbed by careless workmen in installing the heater, or by a person 40 cleaning the heater. When it is considered that these heaters are very frequently used in kitchens, the advantage of this will be apparent.

While I am aware that considerable variation or modification in structural details 45 is possible without departing from my invention, I have not attempted to illustrate or describe such variations or modifications as the disclosure made will enable those skilled in the art to apply my invention as 50 circumstances or taste may dictate, and I desire to be understood as claiming my improvements specifically in the form illustrated as well as broadly within the scope of the appended claims.

Having thus described my invention, what 55 I claim as new and desire to secure by Letters Patent is:

1. The combination of a valve casing provided with a valve seat and a reciprocating 60 member cylinder alined therewith; a valve stem; a valve slidably mounted on said stem, said stem being provided with stops for limiting the movement of the valve and stem relative to each other, the valve when 65 closed being out of engagement with both

stops to permit a limited movement of the valve stem without unseating the valve; an annular reciprocating member arranged in said cylinder; levers pivotally mounted on the head of the cylinder, said valve stem being slotted to receive the inner ends of the levers; links connecting the outer ends of the levers to said reciprocating member; return springs connected to the head of said cylinder and to said reciprocating member; spring supports pivotally connected to said reciprocating member and to said valve, said supports being formed of telescoping sections; and coiled springs arranged on said supports, the support sections being provided with rests for the spring whereby when the plane of the pivots connecting said supports to said reciprocating member moves past the plane of the pivots connecting said supports to said valve, the said springs act on the valve to open and close the same.

2. The combination of a valve casing provided with a valve seat and a reciprocating member cylinder alined therewith; a valve stem; a valve slidably mounted on said stem; an annular reciprocating member arranged in said cylinder; levers pivotally mounted on the head of the cylinder, said valve stem being slotted to receive the inner ends of the levers; links connecting the outer ends of the levers to said reciprocating member; return springs connected to the head of said cylinder and to said reciprocating member; spring supports pivotally connected to said reciprocating member and to said valve, said supports being formed of telescoping sections; and coiled springs arranged on said supports, the support sections being provided with rests for the spring whereby when the plane of the pivots connecting said supports to said reciprocating member moves past the plane of the pivots connecting said supports to said valve, the said springs act on the valve to open and close the same.

3. The combination of a valve casing provided with a reciprocating member cylinder; a valve stem; a valve slidably mounted on said stem, said stem being provided with stops for limiting the movement of the valve and stem relative to each other, the valve when closed being out of engagement with both stops to permit a limited movement of the valve stem without opening the valve; an annular reciprocating member arranged in said cylinder; levers pivotally mounted on the head of the cylinder, said valve stem being slotted to receive the inner ends of the levers; links connecting the outer ends of the levers to said reciprocating member; a return spring connected to the head of said cylinder and said reciprocating member; and connections for said reciprocating member and said valve comprising a

spring arranged to act on said valve to open the same on the inward movement of said reciprocating member and to close the same on the outward movement thereof.

5. 4. The combination of a valve casing provided with a reciprocating member cylinder; a valve stem; a valve slidably mounted on said stem; an annular reciprocating member arranged in said cylinder; levers 10 pivotally mounted on the head of the cylinder, said valve stem being slotted to receive the inner ends of the levers; links connecting the outer ends of the levers to said reciprocating member; a return spring connected to the head of said cylinder and said reciprocating member; and connections for said reciprocating member and said valve comprising a spring arranged to act on said valve to open the same on the inward movement of said reciprocating member and to close the same on the outward movement thereof.

5. The combination of a valve; a valve stem; a reciprocating member; pivotally mounted levers operatively associated with said stem; links connecting the outer ends of the levers to said reciprocating member; a return spring for said reciprocating member; spring supports pivotally connected to 25 said reciprocating member and to said valve, said supports being formed of telescoping sections; and coiled springs arranged on said supports, the support sections being provided with rests for the 30 springs whereby when the plane of the pivots connecting said supports to said reciprocating member moves past the plane of the pivots connecting said supports to said valve, the said springs act to open and close 35 the valve.

6. The combination of a valve; a valve stem; a reciprocating member; pivotally mounted levers operatively associated with said stem; links connecting the outer ends 45 of the levers to said reciprocating member; a return spring for said reciprocating member; and connections for said reciprocating member and said valve comprising a spring arranged to act on said valve to open the 50 same on the inward movement of said reciprocating member and to close the same on the outward movement thereof.

7. In a water heater, the combination with a thermostat of a fuel valve; a valve 55 stem with which said valve is slidably associated, said stem being provided with stops for limiting the movement of the valve and stem relative to each other, the valve when seated being out of engagement with both 60 stops to permit a limited movement of the valve stem without unseating the valve, said thermostat being arranged to actuate said valve stem; a reciprocating member; operating connections for said valve stem 65 whereby the reciprocating member is moved

toward said valve when the stem is actuated by said thermostat; a return spring; and a spring operatively associated with said reciprocating member and valve, and arranged to act on said valve to unseat the same when the reciprocating member is moved past a certain point of its stroke and to seat the valve on its return stroke.

8. In a water heater, the combination with a thermostat of a fuel valve; a valve stem with which said valve is slidably associated; a reciprocating member; operating connections for said valve stem whereby the reciprocating member is moved toward said valve when the stem is actuated by said thermostat; a return spring; and a spring operatively associated with said reciprocating member and valve, and arranged to act on said valve to unseat the same when the reciprocating member is moved past a certain point of its stroke and to seat the valve on its return stroke.

9. In a water heater, the combination with a thermostat, of a fuel valve; a valve stem actuated by said thermostat, said valve stem and valve being movable relative to each other; a reciprocating member actuated by said valve stem; spring supports pivotally connected to said reciprocating member and to said valve, said supports being formed of telescoping sections; and coiled springs arranged on said supports to actuate the valve to open or close the same when the plane of the pivots connecting said supports to said valve.

10. The combination of a valve; a valve stem, said valve stem and valve being movable relative to each other; a reciprocating member actuated by said valve stem; spring supports pivotally connected to said reciprocating member and to said valve, said supports being formed of telescoping sections; and coiled springs arranged on said supports to actuate the valve to open or close the same when the plane of the pivots connecting said supports to said reciprocating member moves past the plane of the pivots connecting said supports to said valve.

11. In a water heater, the combination with a thermostat, of a fuel valve; a valve stem actuated by said thermostat, said valve stem and valve being movable relative to each other; a reciprocating member actuated by said valve stem; a return spring for said reciprocating member; and connections for said reciprocating member and said valve comprising a spring arranged to act on said valve to open the same on the inward movement of said reciprocating member and to close the same on the outward movement thereof.

12. The combination of a valve; a valve stem, said valve stem and valve being movable relative to each other; a reciprocating

member actuated by said valve stem; a return spring for said reciprocating member; and connections for said reciprocating member and said valve comprising a spring arranged to act on said valve to open the same on the inward movement of said reciprocating member and to close the same on the outward movement thereof.

13. In a water heater, the combination with a thermostat, of a valve; a valve stem actuated by said thermostat; a member actuated by said valve stem; and connections for said member and valve comprising a spring arranged to act on said valve to open the same and to close the same when the said member passes a certain point in its movement, said valve stem and valve being independently movable to permit the valve stem to move said member actuated thereby to its valve actuating position without unseating the valve.

14. The combination of a valve; a valve stem; a member actuated by said valve stem; and connections for said member and valve comprising a spring arranged to act on said valve to open the same and to close the same when the said member passes a certain point in its movement, said valve stem and valve being independently movable to permit the valve stem to move said member actuated thereby to its valve actuating position without unseating the valve.

15. In a water heater, the combination with a thermostat, of a valve; a member op-

eratively associated with said thermostat 35 and supported to reciprocate toward and from said valve; connections for said member to said valve comprising a spring support formed of telescoping sections, one section being pivoted to said member and the other to said valve; and a coiled spring arranged on said support to act on said valve whereby when the plane of the pivot connecting said support to said reciprocating member moves past the plane of the pivot 40 connecting said support to said valve, the spring acts on the valve for the purpose specified.

16. The combination of a valve; a member supported to reciprocate toward and from 50 said valve; connections for said member to said valve comprising a spring support formed of telescoping sections, one section being pivoted to said member and the other to said valve; and a coiled spring arranged 55 on said support to act on said valve whereby when the plane of the pivot connecting said support to said reciprocating member moves past the plane of the pivot connecting said support to said valve, the spring acts on the 60 valve for the purpose specified.

In witness whereof, I have hereunto set my hand and seal in the presence of two witnesses.
